UNITED STATES PATENT OFFICE

153,968

DESIGN FOR A PRESSURE COOKER OR THE LIKE

Willard L. Morrison, Jr., West Bend, Wis., assignor to West Bend Aluminum Co., West Bend, Wis., a corporation of Wisconsin

Application October 15, 1947, Serial No. 141,913

Term of patent 14 years

(Cl. D44—1)

To all whom it may concern:

Be it known that I, Willard L. Morrison, Jr., a citizen of the United States, residing at West Bend, in the county of Washington and State of Wisconsin, have invented a new, original, and ornamental Design for a Pressure Cooker or the like, of which the following is a specification, reference being had to the accompanying drawing, forming a part thereof, and in which:

Fig. 1 is a perspective view;

Fig. 2 is a view in end elevation;

Fig. 3 is a top plan view; and

Fig. 4 is a view in side elevation of a pressure cooker, showing my new design.

The numeral seen in Figs. 1 and 3 is shown for illustrative purposes only.

I claim:

The ornamental design for a pressure cooker or the like, as shown and described.

WILLARD L. MORRISON, JR.
